UNITED STATES PATENT OFFICE.

JULIUS J. MILLER, OF ST. JOSEPH, MICHIGAN, ASSIGNOR, BY MESNE ASSIGNMENTS,
TO WIREBOUNDS PATENTS COMPANY, OF KITTERY, MAINE, A CORPORATION OF
MAINE.

BOX-BLANK MACHINE.

1,142,351.

Specification of Letters Patent. Patented June 8, 1915.

Application filed October 30, 1907. Serial No. 399,821.

To all whom it may concern:

Be it known that I, JULIUS J. MILLER, a citizen of the United States of America, and resident of St. Joseph, Berrien county, Michigan, have invented a certain new and useful Improvement in Box-Blank Machines, of which the following is a specification.

My invention relates to box-blank machines of that kind in which the work-holder comprises one or more endless link-belts. In machines of this character, and owing to lost motion, uneven feed, or other reasons, it sometimes happens that the continued operation of the machine for some time results in bringing the work-holder out of step, so to speak, with the staplers—that is to say, the staples are liable to be driven in the wrong places. I now provide means, therefore, of such character that the operator can readjust the work-holder at will, by feeding it forward enough to correct any error that may have developed in the feed. With this arrangement the operator can control the machine in such manner that the staples will always be driven in the proper places in the blanks.

Broadly considered, therefore, the object of my invention is to insure against driving of the staples at points where they are not desired or needed.

More specifically considered, the object of my invention is to provide means controlled by the traveling motion of the work for automatically stopping the driving of staples, while stapled and unstapled blank materials are on the machine, behind and in front of the staplers, for any desired purpose, but more particularly with reference to the operation of the machine in such manner as to prevent the driving of staples in any gaps or spaces necessarily left in the work from time to time, and generally appearing at regular intervals therein.

In the accompanying drawings, Figure 1 is a plan of a machine embodying the principles of my invention. Fig. 2 is a section on line 2—2 in Fig. 1. Fig. 3 is a detail view of the foot lever and clutch mechanism. Fig. 4 is a section on line 4—4 in Fig. 1. Fig. 5 is an enlarged side elevation of a portion of the chain, showing the lever which is tripped by a projection on said chain. Fig. 6 is a plan of the device shown in Fig. 5. Fig. 7 is an enlarged detail sec-

tion view on line 7—7 in Fig. 5. Fig. 8 is a similar section on line 8—8 in Fig. 6. Fig. 9 is a perspective of the lever which is tripped by the chain, and which in turn trips the foot lever. Fig. 10 is a perspective of a portion of said foot lever mechanism.

As thus illustrated, the machine comprises a suitable body A, staplers B, and an endless traveling work-holder C. Said staplers have staple wire feed mechanism b of any suitable character. Said work-holder is actuated intermittently by the feed wheel D and dog d, and said dog is operated by a cam d¹ which engages a lever d². Said lever is connected by a rod d³ with the lever or arm d⁴ upon which the said dog is mounted. Said work-holder carries the cleats and veneer for the blanks, and said staplers secure the binding wires to the same, thus forming the well-known cleat-reinforced and wire-bound box-blanks. As previously explained, it sometimes happens that the machine will be found, after continuous operation for some time, to be driving the staples in the wrong places in the said blank. This is corrected by providing the chain with a projection c adapted to trip the lever E, by engaging the cam projection e on the latter. Said lever has a cam or bevel e¹ which in turn engages the pin e² on the lever e³, which latter is pivoted at e⁴, as clearly shown.

A link e⁵ connects the lever e³ with the catch e⁶, and the latter engages the foot lever e⁷ to hold the clutch closed and keep the machine in operation. Upon a complete revolution or operation of said chain or work-holder the projection c causes the connections to release said foot lever, thus automatically stopping the machine. The hand lever F, which carries the dog f, can then be operated by the attendant to cause the work-holder to feed forward the required distance for correcting any error in the feed. This hand lever is normally engaged by a stop f¹ and controlled by a spring f², and the dog f serves also as a means for preventing back movement of the work-holder when the feed mechanism is operating. It will be seen that any suitable means can be employed for connecting the said foot lever with the clutch G. In this way the entire machine is automatically stopped every time the chain or work-holder

makes a complete revolution. If no error or discrepancy has developed in the feed, then the operator simply presses the foot lever to again start the machine; but if the blanks are then not in proper position to receive the staples, the operator first readjusts the work-holder before again starting the machine. By the hand lever E the machine can be stopped at any time.

10 As the whole machine is stopped, it follows that my invention involves a stapler which is automatically stopped. It also involves a staple wire feed that is automatically stopped by the traveling motion of the work. Also, the work-holder automatically stops itself. As shown, the automatic stopping device is for use in preventing the driving of staples in the wrong place. In other words, I apply this automatic stopping device to the machine as a part of the general scheme or arrangement for preventing the driving of staples at times when they are not desired or needed. But it is obvious that this automatic control of the various mechanisms of the machine by the traveling motion of the work may be employed in various ways, or for, various purposes, without departing from the spirit of my invention.

15 As previously explained, the mechanism for feeding the staple wire is automatically stopped, by means controlled by the feeding motion of the blanks. The other operative portions of the machine are also automatically stopped in the same manner. The purpose of this, as explained, is primarily to prevent the driving of staples in any gaps or spaces left in the work. For example, it prevents the driving of staples between the ends of the blanks, or between the ends of the cleats of the same blank. Of course, and if there were no materials behind the staplers, there would be no necessity for employing this automatic stop action. The machine, however, is constructed in such a manner that materials are approaching the staplers at the time when the stopping of the mechanism is required, and it is for the purpose of properly taking care of the on-coming materials that this automatic stopping provision is made. In other words, the interruption of the staple driving operation takes place, in order to realize the intent and purpose of the invention, when the feed mechanism is in position to feed the materials forward. Thus the feed mechanism including the ratchet D is automatically controlled by instrumentalities including means on the endless traveling work holder, said means, for example, and in this particular form or use of my invention, consisting of the pin c projecting laterally from the link belt. The lever E, which is an element of said instrumentalities, moves about its pivot e⁸ to stop the machine, as previously explained, and also for the purpose of permit-

ting the conveyer to move forward, when necessary, instead of being positively held back by the engagement of the pin c with the engaging portion e of said lever. The said instrumentalities control the operation of the machine, and it follows, therefore, that the conveyer serves in effect and by its forward motion to control itself. Again, and with this arrangement, there are, of course, the staplers B which are automatically controlled (in this case by stopping or rendering them inoperative) by the said conveyer, each stapler being entirely interrupted by the action of the conveyer when the pin c strikes the lever E during the operation of the machine. Primarily, it will be seen, this machine is designed for continuous and uninterrupted operation. But with the said instrumentalities shown and described, whereby the endless conveyer C controls itself, as well as other elements of the machine, the continuous operation is automatically interrupted. In the present case this control exercised by the conveyer is used for stopping the entire machine to guard against the driving of staples in the wrong places. But I do not limit myself to any particular use, or method of use, for this feature of my invention.

What I claim as my invention is:

1. A machine for making wirebound box blanks by fastening sheets to cleats, and by successively wiring together the previously unconnected sections of each blank, comprising staplers for securing the binding wires to the sheets and cleats, an endless traveling conveyer for presenting the sheets and cleats to said staplers in superimposed and spaced relation, a ratchet feed mechanism for actuating said conveyer, and instrumentalities including means on said conveyer to automatically control the operation of said mechanism.

2. A machine for making wirebound box blanks by fastening sheets to cleats, and by successively wiring together the previously unconnected sections of each blank, comprising staplers for securing the binding wires to the sheets and cleats, an endless traveling conveyer for presenting the sheets and cleats to said staplers in superimposed and spaced relation, a ratchet feed mechanism for actuating said conveyer, and instrumentalities including means on said conveyer to automatically govern the operation thereof.

3. A machine for making wirebound box blanks by fastening sheets to cleats, and by successively wiring together the previously unconnected sections of each blank, comprising staplers for securing the binding wires to the sheets and cleats, an endless traveling conveyer for presenting the sheets and cleats to said staplers in superimposed and spaced relation, a ratchet feed mechanism for actu-

ating said conveyer, and instrumentalities including means on said conveyer to automatically control the operation of said staplers.

5 4. A machine for making wirebound box blanks by fastening sheets to cleats, and by successively wiring together the previously unconnected sections of each blank, comprising staplers for securing the binding wires

10 to the sheets and cleats, an endless traveling conveyer for presenting the sheets and cleats to said staplers in superimposed and spaced relation, a ratchet feed mechanism for actuating said conveyer, and instrumentalities including means on said conveyer to automatically render said staplers inoperative.

15 5. A machine for making wirebound box blanks by fastening sheets to cleats, and by successively wiring together the previously unconnected sections of each blank, comprising staplers for securing the binding wires to the sheets and cleats, an endless traveling conveyer for presenting the sheets and cleats to said staplers in superimposed and spaced relation, a ratchet feed mechanism for actuating said conveyer, and instrumentalities including means on said conveyer to automatically render said staplers inoperative, said conveyer comprising a link belt for engaging the cleats, said instrumentalities including a movable element disposed adjacent the side of said belt, and said means projecting laterally from the belt to engage said element.

20 6. A machine for making wirebound box blanks by fastening sheets to cleats, and by successively wiring together the previously unconnected sections of each blank, comprising staplers for securing the binding wires to the sheets and cleats, an endless traveling conveyer for presenting the sheets and cleats to said staplers in superimposed and spaced relation, a ratchet feed mechanism for actuating said conveyer, and instrumentalities including means on said conveyer to automatically control the operation of said mechanism, said conveyer comprising a link belt for engaging the cleats, said instrumentalities including a movable element disposed adjacent the side of said belt, and said means projecting laterally from the belt to engage said element.

25 7. A machine for making wirebound box blanks by fastening sheets to cleats, and by successively wiring together the previously unconnected sections of each blank, comprising staplers for securing the binding wires to the sheets and cleats, an endless traveling conveyer for presenting the sheets and cleats to said staplers in superimposed and spaced relation, a ratchet feed mechanism for actuating said conveyer, and instrumentalities including means on said conveyers to automatically control the operation of said

30 belt for engaging the cleats, said instrumentalities including a movable element disposed adjacent the side of said belt, and said means projecting laterally from the belt to engage said element.

70 8. A machine for making wirebound box blanks by fastening sheets to cleats, and by successively wiring together the previously unconnected sections of each blank, comprising staplers for securing the binding wires to the sheets and cleats, an endless traveling conveyer for presenting the sheets and cleats to said staplers in superimposed and spaced relation, a ratchet feed mechanism for actuating said conveyer, and instrumentalities including means on said conveyer to automatically render said staplers inoperative, said conveyer comprising a link belt for engaging the cleats, said instrumentalities including a movable element disposed adjacent the side of said belt, and said means projecting laterally from the belt to engage said element.

75 9. A machine for making wirebound box blanks by fastening sheets to cleats, and by successively wiring together the previously unconnected sections of each blank, comprising staplers for securing the binding wires to the sheets and cleats, an endless traveling conveyer for presenting the sheets and cleats to said staplers in superimposed and spaced relation, a ratchet feed mechanism for actuating said conveyer, and instrumentalities including means on said conveyer to automatically control the operation of said mechanism, said conveyer comprising a link belt for engaging the cleats, said instrumentalities including a hand lever pivoted adjacent said belt, and said lever having a projection for engaging said means.

80 10. A machine for making wirebound box blanks by fastening sheets to cleats, and by successively wiring together the previously unconnected sections of each blank, comprising staplers for securing the binding wires to the sheets and cleats, an endless traveling conveyer for presenting the sheets and cleats to said staplers in superimposed and spaced relation, a ratchet feed mechanism for actuating said conveyer, and instrumentalities including means on said conveyer to automatically govern the operation thereof, said conveyer comprising a link belt for engaging the cleats, said instrumentalities including a hand lever pivoted adjacent said belt, and said lever having a projection for engaging said means.

85 11. A machine for making wirebound box blanks by fastening sheets to cleats, and by successively wiring together the previously unconnected sections of each blank, comprising staplers for securing the binding wires to the sheets and cleats, an endless traveling conveyer for presenting the sheets and cleats to said staplers in superimposed and spaced

- relation, a ratchet feed mechanism for actuating said conveyer, and instrumentalities including means on said conveyer to automatically control the operation of said staplers, said conveyer comprising a link belt for engaging the cleats, said instrumentalities including a hand lever pivoted adjacent said belt, and said lever having a projection for engaging said means.
- 10 12. A machine for making wirebound box blanks by fastening sheets to cleats, and by successively wiring together the previously unconnected sections of each blank, comprising staplers for securing the binding wires to the sheets and cleats, an endless traveling conveyer for presenting the sheets and cleats to said staplers in superimposed and spaced relation, a ratchet feed mechanism for actuating said conveyer, and instrumentalities including means on said conveyer to automatically render said staplers inoperative, said conveyer comprising a link belt for engaging the cleats, said instrumentalities including a hand lever pivoted adjacent said belt, and said lever having a projection for engaging said means.
- 15 13. A machine for making wirebound box blanks by fastening sheets to cleats, and by successively wiring together the previously unconnected sections of each blank, comprising staplers for securing the binding wires to the sheets and cleats, an endless traveling conveyer for presenting the sheets and cleats to said staplers in superimposed and spaced relation, a ratchet feed mechanism for actuating said conveyer, and instrumentalities including means on said conveyer to automatically control the operation of said staplers, said means projecting laterally from said conveyer, and said instrumentalities comprising a pivoted element arranged to engage said means, which element is movable about its pivot by said means to permit forward movement of said conveyer.
- 20 14. A machine for making wirebound box blanks by fastening sheets to cleats, and by successively wiring together the previously unconnected sections of each blank, comprising staplers for securing the binding wires to the sheets and cleats, an endless traveling conveyer for presenting the sheets and cleats to said staplers in superimposed and spaced relation, a ratchet feed mechanism for actuating said conveyer, and instrumentalities including means on said conveyer to automatically control the operation of said mechanism, said means projecting laterally from said conveyer, and said instrumentalities comprising a pivoted element arranged to engage said means, which element is movable about its pivot by said means to permit forward movement of said conveyer.
- 25 15. A machine for making wirebound box blanks by fastening sheets to cleats, and by successively wiring together the previously unconnected sections of each blank, comprising staplers for securing the binding wires to the sheets and cleats, an endless traveling conveyer for presenting the sheets and cleats to said staplers in superimposed and spaced relation, a ratchet feed mechanism for actuating said conveyer, and instrumentalities including means on said conveyer to automatically render said staplers inoperative, said means projecting laterally from said conveyer, and said instrumentalities comprising a pivoted element arranged to engage said means, which element is movable about its pivot by said means to permit forward movement of said conveyer.

relation, a ratchet feed mechanism for actuating said conveyer, and instrumentalities including means on said conveyer to automatically govern the operation thereof, said means projecting laterally from said conveyer, and said instrumentalities comprising a pivoted element arranged to engage said means, which element is movable about its pivot by said means to permit forward movement of said conveyer.

15 16. A machine for making wirebound box blanks by fastening sheets to cleats, and by successively wiring together the previously unconnected sections of each blank, comprising staplers for securing the binding wires to the sheets and cleats, an endless traveling conveyer for presenting the sheets and cleats to said staplers in superimposed and spaced relation, a ratchet feed mechanism for actuating said conveyer, and instrumentalities including means on said conveyer to automatically control the operation of said staplers, said means projecting laterally from said conveyer, and said instrumentalities comprising a pivoted element arranged to engage said means, which element is movable about its pivot by said means to permit forward movement of said conveyer.

10 17. A machine for making wirebound box blanks by fastening sheets to cleats, and by successively wiring together the previously unconnected sections of each blank, comprising staplers for securing the binding wires to the sheets and cleats, an endless traveling conveyer for presenting the sheets and cleats to said staplers in superimposed and spaced relation, a ratchet feed mechanism for actuating said conveyer, and instrumentalities including means on said conveyer to automatically render said staplers inoperative, said means projecting laterally from said conveyer, and said instrumentalities comprising a pivoted element arranged to engage said means, which element is movable about its pivot by said means to permit forward movement of said conveyer.

Signed by me at St. Joseph, Michigan,
this 18th day of October, 1907.
